PACKAGED ARTICLE

George A. Jagers, Fort Worth, Tex., assignor to Mayfair Industries, Inc., Fort Worth, Tex., a corporation of Texas

Filed May 1, 1961, Ser. No. 106,843
2 Claims. (Cl. 206—63.2)

This invention relates to packaged articles and, more particularly, to an elongated packaged article such as a vaginal tampon applicator. The invention is especially concerned with the provision of tear strips for opening the wrapper enclosing the article.

Tampon applicators are usually enclosed each in a sealed wrapper of paper, cellophane, or the like. A longitudinal tear strip may be provided for opening the wrapper. With such an arrangement, it is possible that the user, in trying to open the wrapper, will simply tear off a corner of the wrapper on the side opposite to the tear strip, thus damaging the wrapper and failing to open it along the line of the tear strip.

It is, therefore, an object of the invention to provide an article having a wrapper with a tear strip arrangement which insures proper opening of the wrapper.

Another object of the invention is to provide an article wrapper that can be opened manually with ease and assurance on the first try.

A further object is to provide such a wrapper that is inexpensive and easily applied to an article to be enclosed therein, that gives good protection to the contents, and that may be readily opened by the average person.

The foregoing and other aims, objects, and advantages of the invention are realized in a wrapped package including a narrow, elongated article, a generally tubular, longitudinally tearable wrapper enclosing the article, and a pair of tear strips adjacent to and extending substantially throughout the length of the wrapper, the tear strips being disposed one on each side of the wrapper. The tear strips preferably are inside the wrapper with the ends of the tear strips being sealed in the end closures of the wrapper.

The invention will be described with greater particularity, and further objects and advantages thereof will be pointed out, in the following detailed description of an exemplary embodiment shown in the accompanying drawing.

In the drawings:

FIG. 1 is a perspective view of a tampon applicator having a wrapper in accordance with the invention;

FIG. 2 is an elevational view of the tampon applicator within the wrapper tube prior to closing the ends of the tube;

FIG. 3 is an elevational view of the wrapped tampon applicator of FIG. 1;

FIG. 4 is a plan view of the wrapped tampon applicator;

FIG. 5 is an enlarged cross-sectional view taken on the line 5—5 of FIG. 4; and

FIG. 6 is a similarly enlarged cross-sectional view taken on the line 6—6 of FIG. 4.

Referring to the drawings, particularly to FIG. 1, there is shown a tampon applicator having the usual tampon tube 10 into the rear end of which is slidably received a plunger tube 11. A tampon, indicated at 12 in FIG. 5, is received in the front end of the tube 10 opposite the end in which the plunger is fitted. A string 13, which may be double-ended, is secured to the rear end of the tampon and extends from the rear end 14 of the plunger tube, the ends of the string being laid forwardly along the outside of the plunger tube. This assembly constitutes an ordinary tampon applicator well known in the art and is exemplary of a narrow, elongated object contained within the wrap-

2

per of the invention, the wrapper being designated by the general reference numeral 15.

Referring to FIGS. 2 and 5, the tampon applicator 10, 11 is seen enclosed in a tube 16 formed from a strip of flexible, tearable, preferably transparent wrapping material such as paper, cellophane, glassine, synthetic resin sheeting, plastic strip or a similar material. The strip of wrapping material extends longitudinally of the tampon applicator, is wrapped circumferentially therearound, and is seamed longitudinally at 17. The seam is lapped and, if desired, it may be sealed by an adhesive composition or, if the nature of the wrapper material so admits, the lapped seam may be heat-sealed. Alternatively, the tube 16 may be of the seamless type.

On opposite sides of the wrapper tube, tear strips 18 and 19 are located. The tear strips extend longitudinally and coextensively of the wrapper tube and, preferably, they are not diametrically opposed but are slightly above the horizontal diameter as seen in FIG. 5, this for reasons to be explained hereinafter. However, the tear strips may be diametrically opposed, if desired. The tear strips are suitably adhered to the inside of the wrapper tube as by means of an adhesive composition or by being heat sealed to the material of the tube. Or the tear strips may merely be located inside and adjacent to the tube without being joined to it. These tear strips preferably are made of tougher material than the material of the wrapper. The tear strips may be colored so that they are easily seen by the user.

As best shown in FIGS. 3 and 4, the completed wrapper has end closures 20 and 21. These are formed by pressing together and sealing the ends of the wrapper tube and thereafter cutting the sealed tube ends. The end cuts or terminal edges 22 are serrated to facilitate tearing the end of the wrapper in opening the package.

Referring to FIGS. 4 and 6, it is seen that the ends of the tear strips 18 and 19 extend through the end closures along the sides thereof and are spaced slightly inwardly from the sides. As noted hereinbefore, the tear strips are not diametrically opposed but are offset so that when the end closures of the wrapper are formed along the horizontal diameter of the tube as seen in FIG. 5, the tear strips will not be folded in the side edges of the end closures but will lie flat and be spaced slightly inwardly from the edges. This arrangement insures a substantially flat end closure. It also improves the tearing action of the strips when the package is opened. This arrangement further enables both tear strips to be plainly seen from the top of the package, as is evident from FIG. 4.

To open the package, the user grasps one of the end closures between the thumbs and forefingers of the right and left hands at opposite sides of the end closure. The righthand fingers pinch the end of one of the tear strips and the lefthand fingers pinch the end of the other tear strip. A tear is made in the end closure. The tear starts at the bottom of one of the serrations between the tear strips and progresses inwardly and generally longitudinally along the end closure. When the tear reaches the tubular part of the wrapper, it deviates to one side or the other of the wrapper, depending upon minute variations in the strength of the wrapper material and the way in which the tearing forces are applied. The tear then progresses to that tear strip toward which the tear has deviated. Further tearing action opens the wrapper longitudinally along the line of that tear strip. The other tear strip does not function to tear its side of the wrapper.

With the present invention, it is immaterial toward which side of the wrapper the tear deviates. The provision of tear strips on both sides of the package assures that one tear strip will function regardless of the direction of deviation of the tear. If but a single tear strip is used, as heretofore, and the tear should progress to the

side of the wrapper without the tear strip, the result would be merely the tearing off of a corner of the wrapper without opening the wrapper throughout its length. The chances are even that this undesired result will occur with but one tear strip; hence, the advantages of employing 5 two tear strips, as in the present invention, are clear.

I claim:

1. A wrapped package comprising:

- (a) a narrow, elongated, generally cylindrical article;
- (b) a generally cylindrical, longitudinally tearable 10 wrapper enclosing said article, the ends of said wrapper extending beyond the ends of said article, each end of said wrapper having diametrically opposed end-wall portions disposed substantially in a single longitudinal diametral plane to provide an 15 end closure having a sharp crease along each lateral edge;
- (c) a pair of tear strips adjacent to the inner surface 20 of said wrapper and extending entirely throughout the length thereof, said tear strips being disposed one on each side of said wrapper, those portions of the tear strips that are next to the sidewalls of said article being adjacent to but slightly offset from said diametral plane, the planes of said portions of said tear strips being disposed at substantial angles to said diametral plane, the ends of said tear strips being sandwiched between the respective opposed end-wall 25 portions of said wrapper, lying substantially in said diametral plane, and being adjacent to the lateral edges of said end closures; and
- (d) means adhesively sealing the opposed end-wall 30 portions of the respective ends of the wrapper to each other and to the ends of the tear strips therebetween whereby a user may open the package by grasping one of the lateral edge portions of one of said end closures between the thumb and forefinger of one hand and the other of the lateral edge portions of 35 said one end closure between the thumb and forefinger of the other hand with the ends of the tear strips between said fingers of the respective hands, longitudinally tearing said one end closure between the ends of said tear strips, and completing the opening of the package by ripping one of said tear strips 40 through one side of said wrapper, the other of said tear strips reinforcing the other side of said one end closure to prevent severance of the grasped portion thereof from the wrapper.

2. A wrapped package comprising:

- (a) a narrow, elongated, generally cylindrical article;
- (b) a generally cylindrical, longitudinally tearable 10 wrapper enclosing said article, the ends of said wrapper extending beyond the ends of said article, each end of said wrapper having diametrically opposed end-wall portions disposed substantially in a single longitudinal diametral plane to provide an end closure having a sharp crease along each lateral edge, the terminal edge of each end closure having serrations therein;
- (c) a pair of tear strips adjacent to the inner surface 15 of said wrapper and extending entirely throughout the length thereof, said tear strips being disposed one on each side of said wrapper, those portions of the tear strips that are next to the sidewalls of said article being adjacent to but slightly offset from said diametral plane, the planes of said portions of said tear strips being disposed at substantial angles to said diametral plane, the ends of said tear strips being sandwiched between the respective opposed end-wall 20 portions of said wrapper, lying substantially in said diametral plane, and being adjacent to the lateral edges of said end closure; and
- (d) means adhesively sealing the opposed end wall 25 portions of the respective ends of the wrapper to each other and to the ends of the tear strips therebetween, whereby a user may open the package by grasping one of the lateral edge portions of one of said end closures between the thumb and forefinger of one hand and the other of the lateral edge portions of said one end closure between the thumb and forefinger of the other hand with the ends of the tear strips between said fingers of the respective hands, longitudinally tearing said one end closure between the ends of said tear strips, and completing the opening of the package by ripping one of said tear strips through one side of said wrapper, the other of 30 said tear strips reinforcing the other side of said one end closure to prevent severance of the grasped portion thereof from the wrapper.
